United States Patent Office

Des. 203,803
Patented Feb. 22, 1966

203,803

BATH TUB

Mike Tecton, 1634 6th St. NW, Oklahoma City, Okla.

Filed June 22, 1964, Ser. No. 80,502

Term of patent 14 years

(Cl. D4—4)

FIG. 1

FIG. 3

FIG. 2

FIG. 1 is a perspective view of a bath tub, showing my new design; and

FIG. 2 is a plan view thereof;

FIG. 3 is a sectional view thereof taken on line 3—3 as indicated in FIG. 2.

I claim:

The ornamental design for a bath tub or the like, substantially as shown.
